Primary Examiner — T Chase Nelson(74) *Attorney, Agent, or Firm* — Karin L. Williams;
Mayer & Williams PC(57) **CLAIM**

The ornamental design for a folding glasses case, as shown and described.

DESCRIPTION

FIG. 1 is a perspective view of a folding glasses case showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side elevational view thereof;

FIG. 7 is a bottom plan view thereof; and,

FIG. 8 is a bottom perspective view thereof, showing the folding glasses case in condition of use; and,

FIG. 9 is a perspective view thereof, showing the folding glasses case in condition of use with folding glasses.

The broken lines in the drawings illustrate environmental structure associated with the folding glasses case in a condition of use. The broken lines and structure depicted form no part of the claimed design.
